ROLL FORMING OF SHEET MATERIAL

Richard H. Shultz, La Grange, and Ruhl T. Schenck,
Chicago, Ill., assignors to Continental Can Company,
Inc., New York, N.Y., a corporation of New York
Filed May 17, 1960, Ser. No. 29,671
8 Claims. (Cl. 72—180)

This invention relates in general to new and useful improvements in the art of forming cylindrical members of sheet material, and more particularly relates to a novel method of roll forming sheet material in the forming of can bodies.

In the operation of a conventional can body maker, the sheet metal blank is moved longitudinally until it is in transverse alignment with a set of rolls, at which time it must be stopped. The direction of movement of the body blank is then changed 90 degrees to put it through the set of rolls, after which it is again stopped. The curved blank then has its direction of movement again changed 90 degrees so that it may continue in its original direction through the remainder of the can body maker. It is, of course, apparent that it is undesirable to change directions of and to start and stop the movement of materials in a forming operation wherein the forming operation is carried out at high speeds.

In view of the foregoing, it is an object of the invention to provide a novel set of rolls wherein a can body blank or a similar blank may be moved longitudinally through the rolls in a continuous operation and the material of the body blank is so stressed that as it exits from the rolls, it begins to assume a generally cylindrical shape with the axis thereof disposed in the general direction of movement.

Another object of the invention is to provide a novel set of rolls through which a blank may be passed in a longitudinal direction, and which rolls are so configurated to result in the plastic deformation of areas of the blank in the manner that as the blank exits from the set of rolls, the plastic deformation of the areas of the blank will result in the blank assuming a generally cylindrical shape having an axis extending longitudinally of the direction of movement of the blank through the rolls.

Another object of the invention is to provide a novel method of roll forming sheet material, such as can body blanks, wherein the sheet blank material is passed between two rolls and while within the rolls, alternating areas thereof are subjected to plastic deformation and elastic deformation so that the stresses within the metal of the flat blank will result in the blank assuming a circular cross-section as it is progressively released by the rolls.

Another object of the invention is to provide a novel can body or other type of tubular member which is self-retaining in its tubular shape due to the existence of areas of plastic deformation.

A further object of the invention is to provide a novel tubular member, such as a can body, wherein the tubular member has been formed from a flat sheet blank and the circular cross-section thereof is accomplished by subjecting areas of the blank to plastic deformation, the areas of plastic deformation being in the form of two sets extending spirally about the tubular member and disposed in crossing relation, the areas of plastic deformation both effecting the shaping of the metal and functioning as a decoration thereto.

Still another object of the invention is to provide a novel method of forming can bodies wherein a can body blank is first passed between a pair of rolls and areas thereof are subjected to plastic deformation so that as the blank passes through the rolls, the blank will be shaped through the formation of the plastic deformed areas into a partial circular cross-section with the axis thereof ex-

2

tending longitudinally of the direction of movement of the blank, and the partially shaped blank being then passed into a conventional body maker wherein it is stressed to its finished form, at which time visual surface irregularities caused by the plastic deformation will disappear, and the can body will have a true circular cross-section.

With the above, and other objects in view that will hereinafter appear, the nature of the invention will be more clearly understood by reference to the following detailed description, the appended claims, and the several views illustrated in the accompanying drawings:

In the drawings:

FIGURE 1 is a schematic perspective view showing a flat sheet blank passing between rolls of a set of rolls formed in accordance with the invention, with the blank having areas thereof deformed, alternating ones of the areas being subjected to plastic deformation and the others being subjected to elastic deformation wherein as the sheet material passes out from between the rolls, it assumes a generally cylindrical shape.

FIGURE 2 is an enlarged fragmentary vertical sectional view taken through the mating portions only of the rolls, and shows the specific configuration thereof, and the shaping of the sheet material while within the rolls, intermediate portions of the rolls and sheet material being omitted.

FIGURE 3 is a perspective view of a cemented can body formed in accordance with the invention.

FIGURE 4 is a transverse sectional view taken through the can body of FIGURE 3 and shows the cross-section thereof.

FIGURE 5 is an enlarged transverse sectional view showing a modified shaping of the blank wherein the tubular cross-section is incomplete.

FIGURE 6 is an enlarged view similar to FIGURE 5, and shows a form of shaping wherein the edges of the blank abut one another in the forming of a complete circle.

FIGURE 7 is an enlarged perspective view of a modified form of can body similar to that of FIGURE 3, but wherein the areas of plastic deformation are arranged in two sets extending spirally about the can body in crossing relation, and the areas of plastic deformation defining an ornamental pattern to enhance the appearance of the can body.

FIGURE 8 is a fragmentary developed view of a roll which may be used in the forming of the can body of FIGURE 7.

It is well known to pass a flat blank through a pair of rolls to effect a curving of the flat blank and with the longitudinal axis of the resultant curved article being disposed at right angles to the direction of movement of the blank through the rolls. However, when this arrangement is used in a can body maker, for example, it is necessary that the blank be stopped and started twice, and that it changes direction of movement 90 degrees twice. This, of course, is undesirable in that it is highly desirable to eliminate all stopping and starting of movement of can body blanks to thus eliminate reciprocating forces and increase the speed of movement of the blank through the can body maker. It is to this end that the present invention relates, the invention proposing to provide a set of rolls through which a blank may be passed longitudinally and wherein the material of the blank is stressed so that the blank will automatically assume a generally circular shape having an axis disposed longitudinally of the direction of movement of the blank.

Reference is made to FIGURE 1, wherein a conventional can body blank B or a similar blank is illustrated. The blank is provided in a flat state and is normally formed of sheet metal. The blank B is passed between a pair of rolls 10 and 11, and as it passes between the rolls

10, 11, the material of the blank B is stressed in a manner to effect the movement of the material of the blank into a generally cylindrical shape as it exits from between the rolls 10 and 11. It is to be understood that the configurations of the rolls 10, 11 are only schematically illustrated in FIGURE 1, and the true section of each rolling surface of the two rolls is best illustrated in FIGURE 2.

The roll 11 is formed of a nonyielding material and is very rigid. The roll 11 is provided with annular ribs 12 which are disposed at spaced intervals along the length of the roll 11. Each rib 12 is relatively narrow and has generally semi-circular cross-section. Thus, each rib 12 presents an arcuate sheet engaging surface. The roll 11 is substantially flat between adjacent ones of the ribs 12.

The roll 10, which roll is disposed uppermost, has a surface defined by a plurality of closely spaced, relatively wide ribs 13. The ribs 13 are also of a partially circular cross-section so as to present an arcuate sheet engaging surface. The radius of curvature of each of the ribs 13 is much greater than that of each of the ribs 12. It is to be noted that the intersection between adjacent ribs 13 defines generally recessed V-areas 14.

The ribs 12 and 13 are disposed in opposed staggered relation. The ribs 12 generally seat within the V-areas 14, and the ribs 13 generally seat in the flattened areas between the ribs 12.

As the blank B passes between the rolls 10, 11, the material thereof is shaped over the ribs 12 and 13. The ribs 12 being relatively sharp as compared to the ribs 13, as the blank B is shaped over the ribs 12, there is set up in the blank B localized areas having plastic deformation. On the other hand, the curvature of the ribs 13 is relatively flat, with the result that the portions of the blank B shaped over the ribs 13 are subject only to elastic deformation. It is to be understood that the deformations of the blank B are greatly exaggerated in FIGURE 2, and that actually the numerous deformations are so minute that in most instances, even the areas of plastic deformation are not readily ascertainable.

As the metal of the blank B passes from between the rolls 10, 11, it progressively stress relieves itself and forms into a cylindrical shape. The final shape of the original blank B may be cylindrical having abutting of the edges of the original blank, cylindrical with overlapped edges, or that of only a partial cylinder, the edges of the blank being spaced apart. These three alternatives are illustrated in FIGURES 6, 4 and 5, respectively.

The shaping of the blank B by passing it between the rolls 10, 11 may function equally as well in a can body having a hooked and lapped seam, one having a lapped seam, or one having a welded seam. In the case of the lapped seam, the lapped edge portions of the original blank may be secured together either by cementing or welding, as desired. A typical lapped seam can body is illustrated in FIGURE 3 and is referred to by C. The details of the lapped edges are clearly shown in the sectional view of FIGURE 4. The can body C may be shaped entirely by the use of the rolls 10, 11, with the shape being maintained only during the cementing operation by a suitable holding means in a conventional manner, or the shaping and cementing of the can body C may be at least partially accomplished in a conventional can body maker.

Reference is now made to FIGURE 6 wherein a sectional view taken through a modified form of can body C is illustrated. The edges of the sheet material are abutted together as at 15 and may be secured together by a welding operation or by other securing means. The abutting together of the edges of the sheet material may either be accomplished by primarily utilizing the set of rolls 10, 11 and suitable guide means, or by utilizing the set of rolls together with a conventional can body maker structure.

In FIGURE 5, the blank B has been only partially shaped and the cross-section thereof is a partial circle, 75

the edges 16, 17 of the blank being widely spaced apart. The blank B may be passed through a conventional can body maker (not shown) and in subsequent forming operations, such as in the wings of the can body maker, the material of the blank is stressed to the finished form for the required can body, after which it is held for bumping, in the case of a can body having a lapped and locked seam, cementing in the case of a lapped seam, and welding in the case of either a lapped or butt seam. When the blank B initially assumes its tubular shape, it has visual surface irregularities along the lines of plastic deformation. However, the stressing of the partially formed blank of FIGURE 5 in a conventional can body maker will result in the disappearance of the visual surface irregularities, and the can body will have a true circular cross-section.

In the blank shaping operation herein described, the ribs 12, 13 extend annularly about the rolls 10, 11, respectively, with the result that the areas of plastic deformation and elastic deformation extend longitudinally of the can body. However, it is not necessary that the areas of deformation extend longitudinally of the can body. If desired, the areas of deformation may extend spirally about the can body, and it is preferred that two sets of spirals be disposed in crossing relation, as is best illustrated in FIGURE 7. Such an arrangement provides a can body which is not subject to paneling, as is the case of the can body formed with the rolls 10, 11. Further, the particular spiral crossing arrangement of the areas of plastic deformation provides a highly ornamental design on the exterior surface of the can body so as to enhance the appearance of the can body. The can body in FIGURE 7 is referred to by the numeral 18 and is shown as having a lapped seam 19. However, the seam could be butt or lapped and locked, if desired. The numerous lines on the surface of the can body 17 indicate lines or areas of plastic deformations, the lines being referred to by the numeral 20.

In FIGURE 8, there is illustrated a fragmentary developed view of a roll which corresponds to the roll 11, but is specifically designed for effecting the deformation of the material from which the can body 18 is formed. This latter roll is referred to in general by the numeral 21 and differs from the roll 11 in that it is provided with two sets of ribs 22 which are spirally arranged and which are disposed in crossing relations. The roll 21 may be used in conjunction with either another rigid roll corresponding to the roll 10, but configurated to match the roll 21, or it may be used in conjunction with a resilient roll, such as one having a hard rubber facing layer. Further, it is to be understood that the roll 11 could be used with a plain roll having a hard rubber facing layer in lieu of the roll 10. However, the roll 10 assists in the deforming of the material of the blank B.

From the foregoing, it will be seen that novel and advantageous provision has been made for carrying out the desired end. However, attention is again directed to the fact that variations may be made in the example method and apparatus disclosed herein without departing from the spirit and scope of the invention, as defined in the appended claims.

We claim:

1. A method of shaping a flat sheet blank into a tubular shape comprising the steps of longitudinally feeding the blank, progressively subjecting spaced areas of the blank while in a flat state to forming forces normal to the direction of feed to plastically deform the blank and effective to cause the blank to tend to assume a generally circular cross section with the axis thereof normal to the forming forces and parallel to the direction of feed, and releasing the stressed portion of the blank to permit the blank to assume a generally circular cross section.

2. A method of rolling a flat sheet blank into a tubular shape comprising the steps of longitudinally feeding the blank between opposed rolls, progressively subjecting

spaced areas of the blank while in a flat state to plastic deformation within the rolls effective to cause the blank to tend to assume a generally circular cross section with the axis thereof normal to the axes of the opposed rolls, and releasing the stressed portion of the blank to permit the blank to assume a generally circular cross section.

3. A method of shaping a flat sheet blank into a tubular shape comprising the steps of longitudinally feeding the blank, progressively subjecting spaced diagonally extending and crossed areas of the blank while in a flat state to forming forces normal to the direction of feed to plastically deform the blank and effective to cause the blank to tend to assume a generally circular cross section with the axis thereof normal to the forming forces and parallel to the direction of feed, and releasing the stressed portion of the blank to permit the blank to assume a generally circular cross section.

4. A method of rolling a flat sheet blank into a tubular shape comprising the steps of longitudinally feeding the blank between opposed rolls, progressively subjecting spaced diagonally extending and crossed areas of the blank while in a flat state to plastic deformation within the rolls effective to cause the blank to tend to assume a generally circular cross section with the axis thereof normal to the axes of the opposed rolls, and releasing the stressed portion of the blank to permit the blank to assume a generally circular cross section.

5. A method of rolling a flat sheet blank into a tubular shape comprising the steps of longitudinally feeding the blank between opposed rolls, progressively subjecting longitudinally extending alternating areas of the blank while in a flat state to plastic deformation effective to cause the blank to tend to assume a generally circular cross section with the axis thereof normal to the axes of the opposed rolls, and releasing the stressed portion of the blank to permit the stressed portion to stress relieve itself and assume a generally circular cross section.

6. A method of forming a can body from a flat sheet blank comprising the steps of longitudinally feeding the blank between opposed rolls, progressively subjecting spaced areas of the blank to plastic deformation within the rolls effective to cause the blank to tend to assume a generally circular cross section, releasing the stressed por-

tion of the blank to permit the blank to assume an open partially circular cross section, and then stressing the blank to its finished circular form through a conventional can body making operation in a conventional can body maker thereby eliminating visual evidence of the areas of plastic deformation.

7. A cylinder-forming roll assembly comprising a set of opposing rolls, a path normal to and from the axis of each roll of the set of opposing rolls whereby a flat sheet blank may be transported to, between and from the rolls along said path, one roll of said set of opposing rolls being provided with first means cooperative with complementary second means on another roll of said set of rolls, said first means and said complementary second means being constructed and arranged to progressively plastically deform a flat sheet blank along linearly extending areas thereof for curling lateral edges of the blank toward each other about an axis parallel to said path whereby said flat sheet blank is formed into a cylinder along the path extending from and normal to the axes of said rolls, said first means comprising a plurality of widely spaced projecting narrow ribs for plastically deforming the flat sheet blank from one side, and the complementary second means comprising a plurality of closely spaced wide ribs in staggered mating relation with said narrow ribs.

8. The cylinder-forming roll assembly of claim 7 wherein said narrow ribs and said wide ribs having arcuate sheet engaging surfaces.
